COMPACT HOLDER WITH RETRACTABLE BRUSH

Filed Sept. 15, 1947

UNITED STATES PATENT OFFICE

2,604,648

COMPACT HOLDER WITH RETRACTABLE BRUSH

Fred Spitalny, Hillside, N. J.

Application September 15, 1947, Serial No. 773,979

2 Claims. (Cl. 15—184)

1

This invention relates to a novel combination of flexible article casing and brush, and more particularly to a brush in combination with a powder compact casing, a comb casing and the like.

Powder compacts are generally provided with soft, flexible casings or containers within which the compact may be inserted and carried in the purse or handbag in order to retain stray powder dust from settling out in the handbag or on the contents thereof.

When the powder compact is removed from the casing and employed to apply powder to the face of the user, the clothing of the user becomes coated with powder dust and, since under normal conditions there is no satisfactory and efficient means for removing this stray powder from the clothing, the user must resort to the unsatisfactory expedient of brushing the stray powder dust from her clothing with her hands.

Accordingly, it is an object of the present invention to provide a flexible casing for a powder compact or the like having a brush combined therewith for removing the stray powder dust from the apparel of the user.

The invention further contemplates the provision of a soft, non-rigid casing or container having an open end for the reception of a powder compact or the like, the casing or container having at its opposite end a movable bristle brush normally held in retracted, inoperative position within the casing and the brush being movable to operative, exposed position upon slight downward pressure of the powder compact against the brush head.

The foregoing objects as well as additional objects and advantages of the invention will be readily apparent in the course of the following detailed description taken in connection with the accompanying drawing illustrating several embodiments of the invention, and wherein:

Fig. 1 is a front view, partly broken away to illustrate internal arrangement, of a powder compact casing and brush, the brush being shown in retracted, inoperative position and the powder compact being retained within the casing.

Fig. 2 is a bottom plan view of Fig. 1.

Fig. 3 is a front view showing the brush in operative, exposed position with the powder compact moved downwardly thereagainst within the casing.

Fig. 4 is a perspective view of a modified form of powder compact casing and brush, the brush being held in fixed, exposed position.

Fig. 5 is a front view of the modification shown in Fig. 4.

2

Fig. 6 is a front view of a comb case combined with a brush.

The casing or container is formed from flexible, pliable material such as fabrics of silk or the like, rubber, etc. and may be provided on its inner surface with soft, fleecy material to prevent marring or scratching the polished surfaces of the powder compact.

Referring first to Figs. 1-3 of the drawing, the casing or container 10 is open at its top end to receive a powder compact 11 or the like, which is shown as being substantially rectangular although it will be understood that the shape of the casing may be varied to conform to the shape and contour of the compact or other article to be retained therewithin.

The bottom end of the casing 10 is closed by a fixed, rigid member 12 which may be secured in place in any desired manner, as by adhesives, tacks, staples or the like. Rigid member 12 is provided with a plurality of apertures 13 for slidably retaining the bristles 14 of a brush head 15 slidably mounted above member 12 within the casing 10. A pair of light-weight compression springs 16 may be interposed between member 12 and brush head 15 adjacent the sides of cover 10 for normally urging brush head 15 and bristles 14 upwardly to the retracted, inoperative position illustrated in Fig. 1. Springs 16 are prevented from buckling by being retained within aligned pairs of recesses 17, 17 in member 12 and brush head 15 respectively.

Means are provided for limiting the upward movement of brush head 15 to prevent the retraction of bristles 14 from the apertures 13 of member 12 and said means may take the form of a chain or retaining element 18 having its ends secured to brush head 15 and member 12 respectively. A pair of aligned recesses 19, 19 is provided to contain chain 18 when the brush head 15 and member 12 are in contact in the operative position of bristles 14 illustrated in Fig. 3.

The compact 11 is normally held in the casing 10 in the position of Fig. 1 with the bristles 14 in concealed, retracted position partially within the interior of the casing and partially within the apertures 13 of fixed member 12. When it is desired to use the brush for removing stray powder dust from the clothing, the top portion of casing 10 may be grasped and slight downward pressure exerted upon compact 11 to move brush head 15 down against fixed member 12, thereby carrying the bristles 14 to the exposed operative position of Fig. 3.

The modification of the invention illustrated

in Figs. 4 and 5 is somewhat simpler in construction than the initial embodiment of the invention and comprises a brush head 20 fixed at the bottom end of a flexible, pliable powder compact casing 21, said brush head carrying the bristles 22. Since the casing 21 is of flexible and pliable material, the brush cannot be used effectively unless a compact 23 or the like is placed within the casing to impart rigidity thereto and adapting the casing to serve as a grasping means or handle for the brush head 20 and the bristles 23.

The article of Figs. 4 and 5 may be fabricated easily and simply by forming the casing 21 from flexible, pliable material as a tubular member 15 and then securing the brush head 20, carrying the bristles 22, in any desired manner.

Fig. 6 illustrates a comb case 25 provided with brush bristles 26 along one edge thereof so that said bristles may be applied to the clothing of 20 the user, the comb case 25 together with the comb 27 retained therewithin serving as a handle for the brush.

Since certain modifications may be made in the article of the invention without departing 25 from the scope thereof, it is intended that all matter contained in the foregoing description and shown in the accompanying drawing be interpreted merely as illustrated and not in a 30 limiting sense.

What is claimed is:

1. A pliable, tubular member, said member being adapted to receive a powder compact through one open end thereof, a rigid element secured to and closing the opposite end thereof, said element having a plurality of apertures 35 therein, a movable brush head mounted within said member above said element, bristles carried by said brush head and slidably retained within said apertures, and springs interposed 40

between said element and said brush head to normally retract said bristles and said brush head to inoperative position with the free ends of the bristles lying within the plane of the outer surface of said rigid element, said brush head being movable against the tension of said springs by downward movement of an inserted compact within said member against said brush head to cause said bristles to project through the apertures of said element to assume an exposed, operative position.

2. A pliable, tubular member in accordance with claim 1, having stop means intersecured between said rigid element and said movable brush head to limit the retraction of said brush head.

FRED SPITALNY.
